Primary Examiner — Rachel A. Voorhies*Assistant Examiner* — Benjamin D. Wannemacher(74) *Attorney, Agent, or Firm* — Warner Norcross + Judd LLP(57) **CLAIM**

The ornamental design for a flare nut crowfoot wrench as shown and described.

DESCRIPTION

FIG. 1 is a perspective view of the flare nut crowfoot wrench embodying the new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

FIGS. 1, 4 and 6 show portions of the flare nut crowfoot wrench in broken lines. The broken line portions form no part of the claimed design.

1 Claim, 7 Drawing Sheets(56)
